UNITED STATES PATENT OFFICE.

ALFRED J. DOWNING, OF TORONTO, ONTARIO, CANADA.

PACKAGE-TIE.

1,294,886.

Specification of Letters Patent.

Patented Feb. 18, 1919.

Application filed April 2, 1918. Serial No. 226,172.

To all whom it may concern:

Be it known that I, ALFRED J. DOWNING, of the city of Toronto, in the county of York, Province of Ontario, Dominion of Canada, have invented certain new and useful Improvements in Package-Ties, of which the following is a specification.

This invention relates to devices adapted for the quick tying and untying of packages and parcels, and my object is to devise a simple, cheap and effective tie which will not only be secure for ordinary purposes, but can be made absolutely secure for mailing purposes without the necessity of tying knots.

I attain my object by means of the constructions hereinafter described and illustrated in the accompanying drawings in which—

20 Figure 1 is a perspective view of my improved tie;

Fig. 2 a perspective view showing the same used in tying a package;

25 Fig. 3 a view of the under side of the device illustrating its mode of operation; and

Fig. 4 a sectional view on an enlarged scale also illustrating the mode of operation of the device.

30 In the drawings like numerals of reference indicate corresponding parts in the different figures.

1 is a disk, preferably stamped from sheet metal. This disk is in the main substantially flat, but the edges 2 are upwardly turned to form a beveled rim. At the center of the disk is formed a hole 3. Concentric with this hole a central recess 4 is formed in the under side of the disk by stamping up the same in the form of the segment of a sphere, an abrupt shoulder being thus formed at the edge of the recess.

The cord 5 may be of any desired length and made of any suitable material. This cord is inserted through the central opening in the disk and a knot is tied at its end to prevent it pulling through. The other end of the cord may also be knotted if desired to prevent the disk sliding off at that end if not carefully handled.

I also form in the disk a slit 6 extending

from the rim as far as the recess 4. This slit is preferably formed with a constricted neck 7 intermediate its ends. This arrangement of the slit is advantageous for two reasons. In the first place the slit can be more accurately and easily punched by a die, and in the second place the string is more easily inserted in the slit and is securely held therein after insertion by the constricted neck.

The operation of the device is substantially as follows. The disk with the knot close to the upper surface of the disk is placed on top of the package and held there by the thumb. The cord is then passed around the parcel or package in any desired manner, and the cord is then drawn around under the disk as shown particularly in Figs. 3 and 4 and twisted around the part 70 of the cord lying within the recess 4. One or more turns may be taken and the free end of the cord jammed between the standing part and the disk in Fig. 4. The package will then be securely tied for all ordinary purposes, but to render the tie safe for mailing purposes or for purposes where rough handling is expected, it is necessary to draw the free end of the cord into the slit 6 and past the constricted neck 7. 80

This device will be found of great value in tying up bundles of letters for delivery by mail carriers, as the tying is much more quickly effected and much time thus saved. It is also valuable for commercial purposes 85 where large numbers of parcels of the same size are to be tied, as the cord may be made of a suitable length for use without waste, so that not only is time saved, but the amount of cord used in tying knots is 90 saved as well as the waste due to the wrappers cutting off more than they actually needed.

In this device the central recess is a very important feature, as it receives and retains the twisted parts of the cord which form in effect a knot, so that the function of the flat part of the disk is merely to frictionally hold the end of the cord to prevent it being unwound. The function of 100 the slit is also the same as that of the flat part of the disk and is supplemental there-

to. At no time is there any normal strain on the cord tending to pull it through the slit or from under the disk.

What I claim as my invention is:—

- 5 In a package tie, a substantially flat sheet metal disk formed with a central hole, an upwardly turned outwardly flaring rim and a segment-spherical dome of small di-

ameter relatively to the disk forming a shallow central recess in the under side concentric with the hole and meeting the under surface of the disk with an abrupt shoulder.

Signed at Toronto, Canada, this 18th day of March, 1918.

ALFRED J. DOWNING.
